source and arranged to coact to close one of
said relays when said machine is in phase with
said source, and a third magnet-coil connect-
ed between unlike phases of said machine and
5 said source and adapted and arranged to close
the other relay when said machine is in phase
with said source.

In witness whereof I have hereunto set my
hand this 21st day of November, 1904.

UNITED STATES PATENT OFFICE.

CHARLES W. HORN, OF CHICAGO, ILLINOIS.

ADDING-MACHINE.

SPECIFICATION forming part of Letters Patent No. 792,041, dated June 13, 1905.

Application filed January 2, 1904. Serial No. 187,487.

To all whom it may concern:

Be it known that I, CHARLES W. HORN, a citizen of the United States, and a resident of Chicago, Cook county, Illinois, have invented certain new and useful Improvements in Adding-Machines; and I do hereby declare that the following is a full, clear, and exact description of the same, reference being had to the accompanying drawings, and to the letters of reference marked thereon, which form a part of this specification.

This invention relates to improvements in adding-machines, and more particularly to an adding-machine adapted to be operated by the fingers and thumb of one hand.

Heretofore adding-machines and comptometers have usually been complicated and expensive in construction, and the multiplicity of parts are subject to frequent derangement, necessitating more or less expensive repairs. So, too, in devices of the kind it is frequently possible by varying the force of the stroke upon the key to occasion a miscount or mistake in the addition.

The object of this invention is to provide a device of the class described capable of operation by means of the fingers and thumb of one hand and so constructed as to provide a positive and accurate count for each key depressed.

It is also an object of the invention to provide a cheap, simple, and durable construction of the class described.

The invention consists in the matters hereinafter described, and more fully pointed out and defined in the appended claims.

In the drawings, Figure 1 is a front elevation of a device embodying my invention. Fig. 2 is a top plan view of the same. Fig. 3 is a front elevation thereof, partly in section and slightly in perspective, showing the front cover or case removed. Fig. 4 is a similar front elevation with the counting-wheels and parts of the operating mechanism removed and the key-bars in section. Fig. 5 is a view similar to Fig. 3, but illustrating a modified form of the locking mechanism for the "5" key. Fig. 6 is an enlarged fragmentary sectional detail of the actuating-gear for the small counting-wheel. Fig. 7 is an en-

larged detail of a part of the modified latch or lock for the large wheel. Fig. 8 is an enlarged detail of a part of the actuating means operated by the keys. Fig. 9 is a similar section taken at one side of that illustrated in Fig. 8. Fig. 10 is a section taken on line 10 10 of Fig. 8. Fig. 11 is a section taken on line 11 11 of Fig. 8. Fig. 12 is a detail view of the actuating means as shown on the right side of the machine. Fig. 13 is an enlarged detail, partly in vertical section, of the smaller counting or hundreds wheel and means for connecting the same on the frame. Fig. 14 is a rear view of said wheel, showing the same detached from the frame.

As shown in said drawings, A indicates a suitable base, of wood or any desired material, upon which is secured an upper finishing or base plate *a*. Rigidly secured on said plate *a* and base A is a frame, which in the present instance consists of a sheet or plate of metal B, bent near its lower edge to afford a flange *b*, adapted for attachment with the base. Said plate extends upwardly and rearwardly from said base, as shown in Figs. 3, 8, and 9. Rigidly secured on the inner side of said frame-plate B by means of screw-bolts extending through its lower margin is a plate, of steel or other suitable metal, B', which is bent inwardly from the frame-plate B and extends upwardly approximately parallel therewith, affording a support for the mechanism to be carried on said frame and which in the present instance comprises a large counter-wheel C, numbered radially on its periphery from "1" to "100" and provided with peripheral ratchet-teeth or serrations equal in number to the numbers upon the periphery and coinciding in position therewith. Said large counter-wheel is provided with a central elongated apertured hub *c*, which is milled externally to afford means for manually engaging the same. Said wheel is rotatively secured upon the inner frame-plate B' by means of a screw-bolt, which passes therethrough and has threaded engagement in an apertured boss *b*' on the plate B' and which acts to hold said large counting-wheel in position to rotate in a given plane. Said boss *b*' spaces said counter-wheel a sufficient distance from the plate B' to permit a five-tooth

gear-wheel C' to be journaled on said plate behind said counter-wheel, as shown in Figs. 3 and 4. Said gear-wheel, as shown, is supported on the frame-plate B' by means of a bolt c², provided with a flattened elongated head c³, at the center of which said gear-wheel is journaled by means of a bolt c⁴. Said gear-wheel is held normally from rotation by the frictional engagement of a coiled spring c⁵ 5 against the same and the plate B' when actuated by the movement of the said counter-wheel. A pin c⁶ (shown in dotted lines in Figs. 3 and 5) is secured on the inner side of said counter-wheel C in position to engage one 10 of the teeth of said five-toothed gear C' and move the same sufficiently to actuate a smaller counter-wheel C² when the counter-wheel C has completed one revolution from "00," or, in other words, counted one hundred. Said 15 smaller counting-wheel C² is secured upon the frame-plate B' by means of a bolt D, which extends through said plate and is provided on the rear side with a nut adapted to hold the same in position. Said bolt D is provided on 20 the inner side of said plate with an enlarged head d, which, as shown in Fig. 13, is provided with a plurality of bosses d' upon its face, which fit into complementary recesses on the inner side of said counting-wheel. An 25 elongated hub c⁶, milled on its outer surface to afford manual engagement, is provided on said wheel, and extending axially through said hub and counting-wheel is a bolt c⁷, which has threaded engagement in the head d of said 30 bolt D. Said counting-wheel on its rear side is shaped to afford a ten-toothed star-shaped gear, as shown in Fig. 14, and on the front side of said wheel are indicated the digits from "0" to "9," inclusive, coinciding with the 35 points of said gear, thus adapting said smaller wheel C² to indicate the number of revolutions of the larger wheel, (each indicating "100.") The outer face of said smaller counting-wheel is in the same plane with the outer face of the 40 larger wheel and the ten-toothed gear thereon is in position for its teeth or points to intermesh successively with the points of the five-toothed wheel C', so that when the larger counting-wheel actuates said five-pointed gear 45 50 55 60 65

cate or count. Pivotedly engaged on the frame near the left side of the machine, as shown in Fig. 4, is a bar or lever E, upon which engages a leaf-spring e, acting to hold said bar normally at the downward limit of 70 its movement. Said bar is provided with four notches on its under side equally spaced from the pivot of the lever and from each other, and extending beneath said lever and engaging each in one of said notches are the key-bars e' e² e³ e⁴, respectively, for the keys "1" 75 to "4," inclusive, and which, as shown, are pivoted centrally on said base-plate a of the machine to afford each of said key-bars the same amplitude of movement. Inasmuch as 80 the distance from the ends of said key-bars at the point of engagement with said lever to the pivot therefor are proportionate it is obvious that actuation thereof by equal movements of said key-bars will proportionately 85 vary the movement of the free end of said lever, or, in other words, the actuation of the key-bar e⁴ will necessarily elevate the free end of said lever four times as high as when actuated by the key-bar e', and in the same manner actuation by the key-bar e³ and e², respectively, will elevate the free end of said lever respectively three times and twice as high as when actuated by the key-bar e'. At the free end of said lever E is provided an upright 90 frame F, of sheet metal, as shown, bent at its bottom to afford a foot-flange f to afford attachment with the base and at its top and middle portion provided with inwardly-directed flanges notched on their ends to provide parallel tongues f' f'', adapted to receive between the same the slide-bar E'. Said slide-bar E' is provided with an aperture at its lower end to receive a suitable projection on the extremity of said lever E and on its upper end affords 95 attachment for a leaf-spring E², which is bent inwardly at its top to engage in the serrations or teeth of the large counting-wheel, as shown in Fig. 3, and possesses sufficient resiliency to permit the same to be sprung laterally as said 100 wheel is revolved thereby, as shown in dotted lines in said figure, so that when said lever is actuated by either of said key-bars the lever E carries said slide-bar E' and the spring E² 105 upwardly into engagement with the teeth, 110 rotating the same to correspond with the numeral on the key actuated. Means are provided for limiting the rotation of the counting-wheel C to the exact distance necessitated by the throw of the free end of said lever E 115 by the key. For this purpose each of said key-bars e' to e⁴, inclusive, is provided beneath the periphery of said wheel each with 120 an upwardly-extending rod or bar e⁵ e⁶ e⁷ e⁸, respectively, rigidly secured thereto, with the upper ends thereof shaped to engage the teeth of said counting-wheel and adapted when the key is forced downwardly to its limit to be brought into positive locking engagement 125 with the teeth of said counting-wheel, there- 130

by holding the same from movement greater than the count of the key caused by a more or less violent blow upon the key.

The "5" key, positioned at the extreme left of the keyboard to be engaged by the right thumb of the operator, is secured upon a key-bar G, which extends inwardly to a point beneath the periphery of the large counter-wheel and in close relation with an upwardly-extending bracket or frame F', similar to the frame or bracket F on the right side of the machine and in like manner provided with a foot-flange f, which affords attachment with the base and at its top is provided with an inwardly-bent flange notched to provide tongues f³, adapted to afford between the same a guide which registers with a corresponding guide formed in an inwardly-directed flange having tongues f⁴ near the center of said bracket, as shown in Fig. 8, and between which is engaged the slide-bar H. At the bottom of said slide-bar is a pin h, which, as shown, projects through a longitudinal slot in the end of said key-bar G, whereby said slide-bar is actuated. Secured on the upper end of said slide-bar is a leaf-spring H', corresponding with the leaf-spring E² on the opposite side of the machine and which, as shown in Figs. 3 and 5, is provided at its upper end with an inwardly and downwardly inclined hook h', adapted to engage the teeth in the counting-wheel and owing to the spring h² pull downwardly when the key is released. Locking mechanism is provided which acts to hold said wheel from being actuated more than five notches or more than the sum of the count of said "5" key and any one of the other keys upon the keyboard. Said locking mechanism, as shown, comprises a bracket or plate I, rigidly secured on the inner face of the frame-plate B and projecting beneath the periphery of the large counting-wheel and having pivotally secured thereon a horizontal trigger-plate i, normally held by a spring i' in position for the inner end thereof to engage the teeth of said counting-wheel, as shown in Fig. 10. The outer end of said trigger-plate extends past the slide-bar H and in close contact therewith, and said slide-bar is shaped on its edge which engages said trigger-plate to afford a cam-surface adapted as the slide-bar is moved upwardly to swing the inner end of the trigger bar or plate inwardly or rearwardly, thus releasing the periphery of the wheel therefrom, as shown in Figs. 3, 8, and 10. Thus when the key "5" is actuated or pressed downwardly the trigger-plate is swung out of engagement with the counting-wheel during the upward movement of the spring-hook H' and is held out of engagement until the inner end of the key-bar G has completed its descent, at which moment the spring again forces the trigger-plate into engagement with the periphery of the wheel. It is obviously important also to release the trigger-plate from the periphery of said wheel when the other keys are actuated; otherwise the wheel would be locked from movement. For this purpose a lever K is pivoted centrally on the frame-plate B and at one end slidably and pivotally engages the free end of the lever E and at its other end, as shown in Fig. 3, extends past the slide-bar H and is provided with a downwardly-directed end k, the lower end of which is bent to afford an arm k', which extends between the bracket F' and slide-bar H and is rigidly secured to and supports the lower end of a sliding trip-bar K', which also bears with one edge against the rear edge of the trigger-plate, as shown in Fig. 9, and is provided with a notch in said edge, which permits said trigger-plate to swing inwardly into engagement with the periphery of said wheel when the key-bars are in their normal position. When, however, one of said keys is actuated, the lever K is actuated thereby, immediately moving the slide-bar K' downwardly, forcing the trigger i out of engagement with the wheel and permitting the same to rotate.

In the modified construction illustrated in Figs. 5 and 7 the lever K and slide-bar K' are omitted, and in lieu thereof a trip-bar K², preferably of spring metal, is rigidly secured on said lever E between the locking-bar e² and the pivot and projects upwardly at the rear of the periphery of said wheel and in position to engage a rearwardly-directed projection k³ on the trigger-plate i², as shown in Fig. 7. When so constructed, the upward movement of the free end of the lever moves the upper end of the arm K² laterally into engagement with the projection k³, thereby swinging the trigger-plate out of engagement with the counting-wheel, as shown in dotted lines in Fig. 7, immediately releasing the same when the lever E is permitted to return to its normal position. Means are also provided for releasing said trigger-plate from the periphery of the large counting-wheel to permit the same to be set back to the "00" or starting position, comprising a bar L, which extends downwardly through the top of the case and at its lower end is seated in said bracket I in close contact with the edge of the trigger-plate, so that when said rod is pressed downwardly the end of said trigger-plate is thrown out of engagement with the counting-wheel. A push-button l is provided at the outer end of said bar, and beneath the same and engaging on the case is a spring l', which normally supports the weight of said rod. In a similar manner a push-pin L' is provided, extending through the case above the counting-wheel C in position for the inner end thereof to be engaged by a pin d⁴, set in the rear side of said counting-wheel, for engagement at a given point to prevent repetition of the count. Ordinarily said pin is so set as to engage said push-pin just before the "0" position is reached on said counting-wheel, so that the

machine locks upon the completion of the count one thousand in the construction herein illustrated. If desired, however, the push-pin may be retracted to either permit the 5 "10" wheel to be again set at "0" or to continue the count for any desired number of thousands preferred.

Fitting closely on and secured to the frame-plate B, which affords the back therefor, is 10 the case M, of sheet metal, which affords a closed casing for the front of the mechanism and is provided with a peripheral flange m, affording the top and side walls therefor. Said plate M is apertured to permit the milled 15 hubs c c⁶ of the counting-wheels to project therethrough, as shown in Figs. 1 and 2, and is also provided with a horizontal slot disposed in alinement with a radius of each of said counting-wheels and over adjacent points 20 on the periphery of each and through which can be seen the numbers indicated for each position of said wheels.

The operation is as follows: The machine constructed and adjusted as described may 25 be actuated to count from one to five by actuating the respective keys, in which event either the spring-blade E² or the blade H', which, as shown, engage on opposite sides of the wheel, causes the large counting-wheel to 30 rotate, and, as before described, the extent of said rotation will be dependent upon the key actuated and can in no instance, owing to the locking mechanism described, exceed a movement corresponding with the number indicated upon the key actuated. Should, however, 35 a digit greater than five be required, the "5" key and either of the other keys may be actuated simultaneously, each affording exactly the same effect as the same keys would 40 produce when actuated singly. For example, should the key "5" and the key "1" be actuated simultaneously, the upward movement of the lever E, actuated by key "1," moves the counting-wheel one notch or one unit 45 while the spring-plate H' is moving upwardly into position to engage and pull the wheel around the five notches or digits, which is the limit of its movement. In the same manner either the key "2," "3," or "4" may be actuated simultaneously with the key "5," said 50 keys each producing their characteristic movement in the counting-wheel before the hook h' engages the appropriate tooth to pull the wheel the number of units indicated upon said 55 "5" key. Thus any of the digits from "1" to "9," inclusive, may be produced either by actuating single keys or the key "5" simultaneously with any one of the other keys upon the keyboard, and in each instance the locking 60 mechanism acts to hold said counting-wheel from movement other than that necessarily produced and indicated by the numeral on the key or keys actuated. In this manner a column of figures may be mechanically and 65 very rapidly added, the counting-wheel hav-

ing been first adjusted, as shown in Fig. 2, with the "00" position on both wheels showing through the observation-aperture. When the large counting-wheel C has been actuated to complete one entire revolution of the pin c⁸, which has a short time previously engaged one of the arms or teeth on the five-toothed gear C' forces said gear around until a tooth thereon engages one of the teeth on the rear side of the counting-wheel C², actuating said 75 counting-wheel one space at the exact moment that the "00" position on the large counting-wheel registers in said observation-aperture, thus the count on the two wheels reading "100" or any number of hundreds equal to 80 the count up to one thousand. Obviously additional counting-wheels may be employed which in a similar manner may register each complete revolution of the counting-wheel C² to indicate the number of thousands counted, 85 and, if preferred, a counting-wheel may be substituted for the wheel C² having any desired number of units upon its periphery, each of said units representing "100" counted by the larger wheel. Obviously, too, the respective counting-wheels may be journaled in any desired or suitable manner upon the frame, and it is obvious that the details for the locking mechanism, as well as minor details of the actuating mechanism, may be varied without departing from the principles of 90 this invention.

I claim as my invention—

1. In an adding-machine, a counting-wheel having a uniformly-notched periphery and having numbers in series arranged thereon, of a lever pivoted adjacent the periphery of said wheel and a plurality of key-bars engaging the first-named lever at points proportional distances apart, means carried on said lever adapted to engage in the notches in said wheel and rotate the same a distance dependent upon the key-bar actuated and means on each key-bar adapted to engage and limit the movement of said wheel.

2. In a machine of the class described a rotative counter-wheel, peripheral teeth thereon, a lever pivoted at one end near the plane of said wheel, key-bars engaging said lever at distances from its fulcrum determined by a numeral on each and a resilient arm pivoted on the free end of the lever acting to engage and rotate the wheel.

3. In a machine of the class described a rotative counter-wheel, a lever pivoted near the plane thereof, key-bars pivoted centrally and each appropriated to a numeral and engaging said lever at a distance from the fulcrum determined by the numeral, a resilient arm carried on the lever and acting to engage and rotate the wheel and means on said key-bars acting to limit the movement of said wheel.

4. In a machine of the class described a rotative counter-wheel, teeth on the periphery numbered consecutively, a lever pivoted ad-

- jacent said wheel and near the plane thereof, a spring holding the same retracted from the wheel, an arm loosely engaged on the end of said lever and keys each indicating a numeral 5 and positively connected with said lever and acting to move said arm into engagement with said wheel and rotate the same a distance corresponding with the numeral on the key actuated.
10. 5. In a machine of the class described a counting-wheel, teeth on the periphery thereof numbered consecutively, a lever pivoted adjacent to said wheel, pivoted key-bars each appropriated to a numeral and engaging said lever at graduated distances from its fulcrum, and an upwardly-extending rod on each key and limiting the movement of the wheel to the numeral on the key actuated.
15. 6. In a machine of the class described a counting-wheel consecutively numbered, teeth on the periphery thereof, key-bars each appropriated to a numeral, means actuated thereby engaging said counter-wheel, the actuating means operated by one key acting on the opposite side of the wheel from the others and adapted to operate conjointly with any other key and guides adapted to hold said actuating means in position.
7. In a machine of the class described, a rotative counter-wheel, equally-spaced, consecutively-numbered teeth thereon, a plurality of key-bars each appropriated to a numeral, means operated thereby adapted to rotate the wheel to correspond with the numeral of the key-bar actuated, one of said key-bars acting on the periphery of the wheel on the opposite side the center from the other, the key-actuated means on one side the wheel acting to pull and on the other to push the wheel in making the count, adapting the single key to operate with any one of the oppositely-disposed keys in making the count, and locking means for each key preventing false count.
8. In a computing-machine a rotative counting-wheel having numbers consecutively arranged near its periphery, keys numbered from "1" to "4" inclusive, a pawl operated thereby acting to rotate said wheel to correspond with the number on the key operated,
- a "5" key, a pawl operated thereby acting to 50 rotate said wheel correspondingly and adapted to operate independently and with any one other key to rotate said wheel to correspond with the sum of the numbers on said keys a 55 guide for each of said pawls and a close case provided with an aperture through which the number indicating the total count may be seen.
9. In a computing-machine a rotative consecutively-numbered counter-wheel, four keys appropriated to the digits "1" to "4" inclusive, means operated by each acting to rotate said wheel to correspond with the digit of the key operated and an upwardly-extending arm on each key adapted to lock the wheel when the key has reached its downward limit. 60
10. In a computing-machine, a rotative counting-wheel having numbers consecutively arranged on its periphery, key-bars numbered from "1" to "4" inclusive, a spring-pawl operated thereby adapted to rotate said wheel a 70 space corresponding to the key-bars operated, a "5" key, a pawl operated thereby adapted to engage the opposite side of the wheel, a trigger adapted to normally lock said wheel from rotation, means for releasing said trigger when the "5" key is operated and a lever actuated by the other keys adapted to operate said trigger. 75
11. In a computing-machine, the combination with a counting-wheel, a lever pivoted beneath the same, a pawl on the free end thereof adapted to operate said wheel, keys numbered from "1" to "4" inclusive adapted to operate said lever, a "5" key, a pawl thereon adapted to operate said wheel both independently 80 and in conjunction with the aforesaid keys, a trigger operated by said "5" key, a lever slidably engaged with the free end of the key-operated lever and a trip-bar thereon adapted to release said wheel when the first-named keys 85 are operated. 90

In testimony whereof I have hereunto subscribed my name in the presence of two subscribing witnesses.

CHARLES W. HORN.
